CLAIM

The ornamental design for a mobile phone, as shown and described.

DESCRIPTION

FIG. 1 is a front perspective view of a mobile phone showing my new design according to a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof;

FIG. 9 is a front perspective view of a mobile phone showing my new design according to the first embodiment shown in FIGS. 1-8 albeit with alternate environment;

FIG. 10 is a front elevation view thereof;

FIG. 11 is a rear elevation view thereof;

FIG. 12 is a left side elevation view thereof;

FIG. 13 is a right side elevation view thereof;

FIG. 14 is a top plan view thereof;

FIG. 15 is a bottom plan view thereof;

(Continued)

FIG. 16 is a rear perspective view thereof;
 FIG. 17 is a front perspective view of a mobile phone showing my new design according to the second embodiment;
 FIG. 18 is a front elevation view thereof;
 FIG. 19 is a rear elevation view thereof;
 FIG. 20 is a left side elevation view thereof;
 FIG. 21 is a right side elevation view thereof;
 FIG. 22 is a top plan view thereof;
 FIG. 23 is a bottom plan view thereof;
 FIG. 24 is a rear perspective view thereof;
 FIG. 25 is a front perspective view of a mobile phone showing my new design according to the second embodiment shown in FIGS. 17-24 albeit with alternate environment;
 FIG. 26 is a front elevation view thereof;
 FIG. 27 is a rear elevation view thereof;
 FIG. 28 is a left side elevation view thereof;
 FIG. 29 is a right side elevation view thereof;
 FIG. 30 is a top plan view thereof;
 FIG. 31 is a bottom plan view thereof; and,
 FIG. 32 is a rear perspective view thereof.

The broken lines shown in the figures that are immediately adjacent to the shaded areas and define unshaded regions, represent the bounds of the claim. All other broken lines, including the features within broken line boundaries and the display are directed to environment. The broken lines form no part of the claimed design.

1 Claim, 28 Drawing Sheets
